US00D840392S

(12) **United States Design Patent** (10) **Patent No.:** **US D840,392 S**
(45) **Date of Patent:** ** *Feb. 12, 2019

(54) **COMPUTING DEVICE**

(71) Applicant: **Intel Corporation**, Santa Clara, CA (US)

(72) Inventors: **Douglas Satzger**, Santa Clara, CA (US); **Sameer Sharma**, Santa Clara, CA (US); **Gadi Amit**, San Francisco, CA (US); **Yoshikazu Hoshino**, San Francisco, CA (US)

(73) Assignee: **Intel Corporation**, Santa Clara, CA (US)

(*) Notice: This patent is subject to a terminal disclaimer.

(**) Term: **14 Years**

(21) Appl. No.: **29/513,137**

(22) Filed: **Dec. 27, 2014**

(51) LOC (11) Cl. **14-02**

(52) U.S. Cl.

USPC **D14/341**

CLAIM

The ornamental design for a computing device, as shown and described.

DESCRIPTION

FIG. 1 is a perspective view illustrating a computing device according to one embodiment;

FIG. 2 is a back view thereof;

FIG. 3 is a front view thereof;

FIG. 4 is a side view thereof;

FIG. 5 is another side view thereof;

FIG. 6 is a top view thereof; and,

FIG. 7 is a bottom view thereof.

The evenly-spaced broken lines in FIGS. 1-7 illustrate portions of the computing device that form no part of the claimed design.

1 Claim, 5 Drawing Sheets
